UNITED STATES PATENT OFFICE.

GILES S. MOORE, OF INDIANAPOLIS, INDIANA, ASSIGNOR TO TROLLEY SHOE-WHEEL COMPANY, OF INDIANAPOLIS, INDIANA, A CORPORATION OF INDIANA.

TROLLEY WHEEL.

Application filed May 31, 1923. Serial No. 642,573.

To all whom it may concern:

Be it known that I, GILES S. MOORE, a citizen of the United States, residing at Indianapolis, in the county of Marion and State of Indiana, have invented certain new and useful Improvements in Trolley Wheels, of which the following is a specification.

My said invention relates to a trolley having a sliding contact shoe for normal engagement with the wire. It is an object of the invention to provide means whereby the shoe will be replaced during backward movement of the trolley by a wheel which can rotate backward freely and do away 15 with any danger of displacing the trolley from the wire.

A further object of the invention is to provide a reversible trolley with a pair of friction shoes which may be alternately turned into operative position to increase 20 the wear or to temporarily replace a worn shoe until the same can be repaired.

Referring to the accompanying drawings, which are made a part hereof and on which 25 similar reference characters indicate similar parts,

Figure 1 is a side elevation of my device with parts broken away showing the trolley in the position assumed during forward 30 movement of the car in the direction of the arrow, and

Figure 2 is a similar elevation of the device in the position assumed by it during rearward movement of the car in the direction of the arrow.

In the drawings reference character 10 indicates a trolley wire of ordinary construction and 11 indicates a harp having forks 12 with a cross bar 13 between them, said 40 forks being connected at their upper ends by a bolt 14 forming a pivot for a pair of brackets, only one of which appears in the drawings. The bracket has a pair of arms 15 at opposite sides and a central arm 16, a bolt 17 connecting the arms 16 of the two brackets and providing a journal for a trolley wheel 18 having the usual flanges for engaging the wire. Preferably said trolley 45 wheel has a tread consisting of a series of removable shoes as in Patent No. 1,382,664, of June 28, 1921. Each of the pairs of arms 15 supports at their outer end a shoe 19 adapted for sliding contact with the trolley wire, this shoe preferably consisting of a 50 substantially hollow member of sheet iron

having upstanding flanges between which is a removable wear plate 20 indicated in dotted lines in Figure 1. A connector 21 which may be of spring material is bent near opposite ends at 22 to provide shoulders 60 against which the adjacent ends of the shoes may rest, this being for convenience in positioning the shoes which are secured to the outer ends of the connector by lugs 23 passing through ears 24 on the shoes, the lugs 65 being preferably headed over to secure the shoes in place. The connector midway between its ends is provided with a bolt 25 adapted to be positioned in one or the other of two holes indicated at 26 so as to strike 70 against the cross bar 13 which acts as a stop to limit the movement of the shoe away from working position. In the operation of my device it will be seen that the shoe which is in operative position will remain in sliding 75 contact with the trolley wire as indicated in Figure 1 so long as the car moves in a forward direction carrying the trolley with it. Should the movement of the car be reversed the friction between the wire and the shoe 80 combined with the action of gravity will move the parts toward the position indicated in Figure 2 where the revolving wheel 85 engages the wire. This action is facilitated by the relation of the shoes to the wheel, the adjacent noses of the shoes extending between the flanges of the wheel almost to the track for the wire. One of the abutments 27 will strike against the bar 13 (for which may be substituted a lug on the fork or any 90 other equivalent structure) thereby limiting the pivotal movement of the brackets and the parts carried thereby. Should the shoe which is in working position become overheated or otherwise damaged or 95 unduly worn the harp 11 can be rotated about the axis of the trolley pole so as to bring the other shoe 19 into operative position after which the operation of the device will be as before. It has already been explained 100 how the bolt 25 acts as a stop to hold either shoe in working position against the wire.

It will be obvious to those skilled in the art that various modifications may be made 105 in the device without departing from the spirit of the invention and therefore I do not limit myself to what is shown in the drawings and described in the specification, but only as indicated in the appended claims. 110

Having thus fully described my said invention, what I claim as new and desire to secure by Letters Patent, is:

1. A reversible trolley comprising a harp, a pair of sliding contact shoes, and means on the harp for sustaining the shoes in angular relation to each other whereby rotation of the harp on its longitudinal axis will serve to bring the shoes alternately into position for engagement with the trolley wire, substantially as set forth.
2. In a trolley, a harp, a pair of sliding contact shoes carried thereby and adapted to be either alternately engaged with the trolley wire or both disengaged therefrom, a wheel for engaging the wire, said wheel and shoes having opposing flanges for guiding the wire, and said shoes have pointed ends located between the flanges of the wheel, substantially as set forth.
3. In a trolley, a harp, a bracket pivotally supported thereby, a wheel on the bracket, shoes supported by the bracket at opposite sides of the wheel, and means permitting the wheel and one of the shoes to be brought alternately into engagement with the wire according to the direction of movement of the car, substantially as set forth.
4. In a trolley, a reversible harp, a bracket pivotally supported thereby, a wheel on the bracket, shoes supported by the bracket at opposite sides of the wheel, and means permitting the wheel and one of the shoes to be brought alternately into engagement with the wire in one position of the harp and the other shoe and the wheel in the reverse position of the harp, substantially as set forth.
5. In a trolley, a harp, a bracket pivotally supported thereby, a wheel on the bracket, shoes supported by the bracket at opposite sides of the wheel, means permitting the wheel and one of the shoes to be brought alternately into engagement with the wire according to the direction of movement of the car, and means for limiting the pivotal movement of the bracket in opposite directions, substantially as set forth.
6. In a trolley, a harp, a wheel supported thereby, a pair of shoes also supported by the harp, means permitting the wheel and one of the shoes to be brought alternately and automatically into engagement with the wire according to the direction of the movement of the car, and means permitting the other shoe and the wheel to be brought alternately and automatically into engagement with the wire on reversal of the direction of movement of the car by rotation of the trolley pole on its axis, substantially as set forth.
7. In a trolley, a harp, a wheel supported thereby, a pair of shoes also supported by the harp, means permitting the wheel and one of the shoes to be brought alternately into engagement with the wire according to the direction of the movement of the car, and means permitting the other shoe and the wheel to be brought alternately into engagement with the wire on reversal of the direction of movement of the car by rotation of the trolley pole on its axis, substantially as set forth.
8. In a trolley, a harp, a bracket pivotally supported on the harp, shoes at opposite sides of the bracket, a wheel intermediate said shoes, a connector between said shoes, stops on the connector for locating the shoes, and means for securing the shoes to the connector, substantially as set forth.
9. In a trolley, a harp, a bracket pivotally supported on the harp, shoes at opposite sides of the bracket, a wheel intermediate said shoes, a connector between said shoes, an abutment carried by the harp, and stops on the connector for co-acting with said abutment to limit the pivotal movement of the bracket, substantially as set forth.
10. In a trolley, a harp, a bracket pivotally supported on the harp, shoes at opposite sides of the bracket, a wheel intermediate said shoes, a connector between said shoes, said trolley being reversible by movement of the harp about the axis of the trolley pole, an abutment on the harp, and stops on the connector adapted to engage said abutment to limit the pivotal movement of the bracket in either of said reversible positions, substantially as set forth.
11. In a trolley, a harp, a trolley wheel on the harp, a sliding contact shoe carried by the harp, flanges on the shoe and the wheel forming grooves for the trolley wire, and a nose on the shoe extending between the flanges on the wheel, substantially as set forth.
12. A trolley construction for making contact with a trolley wire, comprising a supporting pole, a frame member pivotally mounted on said pole, a pair of oppositely positioned sliding contact shoes supported by said frame member, and a wheel pivotally mounted on said frame member in position to be brought into contact with said trolley wire when moving in one direction and thrown out of contact when moving in the opposite direction.
13. A trolley construction for making contact with a trolley wire, comprising a supporting pole, a frame member pivotally mounted on said pole, a pair of sliding contact shoes positioned on opposite sides of said frame and having their ends joined by a rigid connection, and a flanged trolley wheel rotatably mounted on said frame having a portion thereof extending between the contact surfaces of said shoes, whereby said wheel may be thrown into engagement with said trolley wire while moved in one direction.

direction and be thrown out of engagement therewith when moved in the opposite direction.

14. In a trolley for an electrically driven vehicle, a pair of spaced sliding contacts, a rolling contact, and a reversible support for said contacts whereby the rolling contact engages the trolley wire only when the vehicle moves in one direction and the sliding contacts engage alternatively with the trolley wire when the trolley is moving in the other direction, substantially as set forth.

15. In a trolley for vehicles, a trolley wheel, a pair of sliding shoes and a reversible support for said parts whereby the shoes only may engage alternatively with the trolley wire as the vehicle moves in one direction, and the wheel only as the vehicle moves in the other direction, substantially as set forth.

16. In a trolley for vehicles, a harp, a reversible pivoted support on the harp, a rolling contact carried thereby, sliding contacts on the support at opposite sides of the rolling contact, and means for limiting the swinging movement of the support on the

harp in either of its interchangeable positions, substantially as set forth.

17. In a trolley, a harp and a pair of sliding contact shoes carried thereby adapted for alternate engagement with the trolley wire, substantially as set forth.

18. In a trolley, a harp, a pair of sliding contact shoes carried thereby adapted to be either alternately engaged with the trolley wire or both disengaged therefrom, and additional means for engaging the wire when both shoes are disengaged therefrom, substantially as set forth.

19. In a trolley, a harp, a pair of sliding contact shoes carried thereby and adapted to be either alternately engaged with the trolley wire or both disengaged therefrom, and a wheel for engaging the wire when both shoes are disengaged therefrom, substantially as set forth.

In witness whereof, I have hereunto set my hand and seal at Indianapolis, Indiana this 29th day of May, A. D. nineteen hundred and twenty-three.

GILES S. MOORE. [L.S.]
